UNITED STATES PATENT OFFICE.

ROBERT JAMES PIERSOL, OF ENGLEMINE, CALIFORNIA.

ORE-SEPARATOR.

1,335,600.

Specification of Letters Patent. Patented Mar. 30, 1920.

Application filed May 21, 1919. Serial No. 298,619.

To all whom it may concern:

Be it known that I, ROBERT J. PIERSOL, a citizen of the United States, and a resident of Engelmire, in the county of Plumas and State of California, have invented a new and Improved Ore-Separator, of which the following is a full, clear, and exact description.

The present invention relates to new and useful improvements in machines for concentrating ores, and pertains more particularly to machines by which this operation is carried out by what is known as the "flotation process." In this process the pulp which embodies finely divided ore, a liquid such as water, and a frothing agent consisting of a suitable oil, is subjected to a suitable agitating and aerating process, and it is the primary object of this invention to increase the efficiency of this agitating and aerating process.

It is a well-known fact in the art that the sulfids in the gangue have an affinity for and adhere to the bubbles which arise to the surface of the pulp carrying the sulfids with them.

Processes in which both the number and size of these bubbles are increased are numerous, such, for example, as submitting the pulp to the action of a vacuum; forcing air under pressure through the body of the pulp; liberating the gases by chemical reaction obtained by introducing the chemicals directly into the pulp; introducing air to the pulp by forcing it from the extremities of the blades of the agitating element, and other processes of less efficiency than those herein mentioned.

By actual experiment it has been found that if the pulp is subjected to the action of a rotating agitator which is only partially submerged therein, a more satisfactory aeration of the pulp is obtained. It has further been noticed that these results are obtained with a smaller quantity of frothing oil, a less violent agitation, and that the separating process is thoroughly accomplished with a fewer number of retreatments of the pulp.

With the above and other objects in view, reference is had to the accompanying drawings in which:

Figure 1 is a vertical sectional view taken on the line 1--1 of Fig. 3;

Fig. 2 is a similar view taken on the line 2--2 of Fig. 3;

Fig. 3 is a horizontal sectional view taken on the line 3--3 of Fig. 1.

Referring more particularly to the drawings, the device comprises an agitating chamber 5, and a spitzkasten 6, the agitating chamber 5 and spitzkasten 6 being separated from each other by means of a vertical partition 7. Mounted in bearings 8, is a transversely extending shaft 9, which shaft is positioned about half-way of the vertical dimension of the agitating chamber 5, and rigidly carried by the shaft 9 and mounted for rotation therewith, is an agitator 10, which comprises a hub portion 70 from which project a plurality of equidistantly spaced blades 11.

Mounted on one end of the shaft 9, is a driving pulley 12, which is adapted to connect with any suitable source of power, by means of a belt not herein shown.

The partition 7 separating the agitating chamber 5 and the spitzkasten 6 is provided with an angularly disposed opening 18, near the upper edge thereof, and below the extremities of the agitating blades 11, when in their vertical position, and said opening, has an angularly disposed wall 14, which projects into the agitating chamber 5, and an angularly disposed wall 15, which projects inwardly of the spitzkasten 6. The lower edge of the partition 7 is provided with an angularly disposed wall 16, which is spaced from the bottom wall 17 of the spitzkasten to provide an opening 18 leading from the spitzkasten into the agitating chamber 5. Located in the spitzkasten 6, adjacent the partition 7, is an angular partition 17, which together with the partition 18, form two chambers 19 and 20. The chamber 19 communicates with the interior of the spitzkasten by means of a passage 21, which leads under the portion 22 of the angular partition 17, and the chamber 20 communicates with the agitating chamber 5 by means of a passageway 23, which leads under the inclined projecting wall 24 of the partition 7. The partition 7 is likewise provided with a passage 25, which leads from the agitating chamber 5 into the chamber 20.

Extending transversely of the spitzkasten 6, near one end thereof, is a shaft 26, and mounted on one end thereof is a pulley 27. Passing around this pulley 27 and a pulley 28 secured to the shaft 9, is a belt 29, which serves to drive the pulley 27 upon operation of the agitating blades 11. Mounted on the

shaft 26 and rotatable therewith, are oppositely disposed blades 30, which serve to convey the froth into the discharge passage 31, from whence it is conveyed to another 5 device of like character for the purpose of repeating the operation, or to any suitable treating machine.

The reference character 32 designates a discharge pipe from the spitzkasten by 10 means of which the gangue is drawn therefrom and said discharge pipe 32 is controlled by means of a valve 33.

Having thus described the invention, the 15 operation is as follows: The pulp is introduced into the agitating chamber 5 by means of the extension 34 thereof, as shown by the arrows in Fig. 1. When sufficient quantity of the pulp has been introduced, the 20 agitator is rotated in the direction of the arrow shown in Fig. 1. This rotation of the agitator produces a beating action of the pulp and, as shown in Figs. 1 and 2, the pulp is lifted by the agitating blades and introduced into the passage 13 between the 25 agitating chamber 5 and the spitzkasten 6. As shown in Figs. 1 and 2, the quantity of pulp in the agitating chamber 5 is only sufficient to partially submerge the agitating blades 11, and by this construction, it has 30 been found that a better aeration of the pulp is obtained since not only is the air taken down into the pulp by the blades at the right-hand side of Figs. 1 and 2, but the pulp is lifted and submitted to the action

of the air in the upper part of the agitating 35 chamber on the left-hand side of the agitating blades in Figs. 1 and 2.

The froth produced by the agitating blades 11 rises to the surface in the spitzkasten, as shown in Figs. 1 and 2, and is 40 discharged by means of the rotating members 30 in a manner heretofore described, the gangue settling to the bottom of the spitzkasten and passing back into the agitating chamber below the inclined wall 12, 45 and the liquid passing into the agitating chamber 5 by means of the passageways 23 and 25.

Having thus described the invention, what 50 is claimed is:

A device of the character described comprising an agitating chamber, a spitzkasten, a partition for separating said agitating chamber and spitzkasten, means provided in the upper portion of said partition for communicating said agitating chamber with said spitzkasten, a partition mounted at one end of the spitzkasten to provide a chamber in said spitzkasten, said partition having its upper edge arranged below the top 55 edge of the sides of said spitzkasten for permitting of the contents of said spitzkasten flowing over the top of said partition into said chamber, and means at the base of said first mentioned partition for 60 communicating said chamber with said agitating chamber.

ROBERT JAMES PIERSOL.
